Inventor:
Michael Tretick
By Chapman & Ferguson
Attorney:

UNITED STATES PATENT OFFICE.

MICHAEL TRETICK, OF BALTIMORE, MARYLAND.

TELEPHONE ARM AND CALL-CARD HOLDER.

Application filed July 18, 1921. Serial No. 485,530.

To all whom it may concern:

Be it known that I, MICHAEL TRETICK, a citizen of the United States, residing at Baltimore, in the State of Maryland, have invented certain new and useful Improvements in Telephone Arms and Call-Card Holders, of which the following is a specification.

This invention relates to improvements in telephone arms and call card holders. The object of the invention is to provide a simple and efficient means whereby cards on which various calls are printed are arranged in close proximity to the telephone.

The invention consists of the novel construction and arrangement of the parts and combination of parts hereinafter more fully set forth in the following specification and pointed out in detail in the appended claim.

In the accompanying drawing:—

Figure 1 is a side elevation of my invention.

Figure 2 is a top plan view of Fig. 1.

Figure 3 is an enlarged detail view of part of the call cards and holders.

Figure 4 is a top plan view of the rod showing the detached rings.

Referring to the accompanying drawings forming part of this specification and in which like reference numerals designate like parts throughout the several views thereof, 1 designates a clamp by means of which the device is secured to a desk, table or other article of furniture and provided with a thumb screw 2 to hold the same in position thereon. The folding arms 3, 4

and 5 are pivoted and the arm 3 is pivoted to the upper end of the clamp 1. The outer end of the arm 5 is provided with a clamp 6 to which the telephone 7 is secured. A 40 rod 8 forms the pivot between the arms 4 and 5 and projects upwardly from the folding arms and is provided with a number of apertures 9 in which are secured the rings 10 which latter are adapted to open to receive the call cards 11. Any number of call cards may be employed on which are printed or written the names and numbers of the various telephone calls.

It will thus be seen that by having the 50 telephone call cards close to the telephone the call numbers will always be accessible to the user of the phone.

Having thus described my invention what I claim is:

A telephone arm and call card holder comprising a folding arm comprising a number of pivoted sections, a clamp pivoted to one end of said arm to hold the latter in position, a thumb-screw fitted in said 60 clamp, means at the other end of said arm adapted to hold a telephone, a rod projecting upward from said arm and forming the pivot between two of the sections of said arm and having a number of apertures 65 therein, a number of split rings fitted in said apertures, and a number of call cards adapted to be held to said rod by said rings.

In testimony whereof I affix my signature.

MICHAEL TRETICK,
